SOUND CONTROL APPARATUS

Creed M. Chorpening, Youngstown, Ohio, assignor to Astatic Microphone Laboratory, Inc., Youngstown, Ohio, a corporation of Ohio

Application September 29, 1938, Serial No. 232,357

4 Claims. (Cl. 179—100.4)

This invention relates to a sound reproducing system, and more particularly to a method and apparatus for controlling sound reproduced from a record. The invention is especially applicable to a system in which a condenser type generator, as a piezo-electric crystal, is utilized as the pick-up element and has as its principal object the provision of a pick-up circuit which will simultaneously compensate for low frequency deficiency in the amplitude of the recording and provide frequency discriminating characteristics whereby the sound reproduced will be of high fidelity and controlled tone.

For reasons well understood in the art it is common practice to record the lower frequencies (below approximately 250 cycles per second) at constant wave amplitude and the higher frequencies at constant needle velocity which results in substantial curtailment of the volume or general amplitude of the lower frequencies. Inasmuch as a translating device of the kind mentioned, if sufficient load resistance is provided, has an output proportional to the wave amplitude or amplitude of vibration regardless of frequency, its normal output is constant for the lower frequencies and declines steadily as the higher frequencies are reached. Now by providing means discriminating against the lower frequencies the output of the pick-up may be rendered substantially constant throughout the audio frequency range thus providing a response of high fidelity.

In the reproduction of sound and particularly in reproduction of sound from records a certain amount of objectional noise resulting from extraneous pick-up of signals composed principally of the higher frequencies is reproduced and unless some means is provided to discriminate against such frequencies the final reproduction may be unsatisfactory. Also it is desirable to utilize such means to compensate for variations in the characteristics of the pick-up device, for desired low or high frequency preponderance in the sound being picked up, for imperfections in the frequency response of the loudspeaker, and for other purposes well understood in the art.

Accordingly, a further object of the invention is the provision of a pickup circuit requiring but simply constructed and inexpensive electrical accessories by means of which the tonal qualities of the sound being reproduced may be satisfactorily controlled simply by actuating a three position switch of conventional design and connected into the signal circuit between the pickup and the amplifier.

The invention will be described by way of example with reference to a reproducing system shown schematically in the drawing in which the pickup device hereinbefore mentioned is a translator of the piezo-electric crystal type, the invention being particularly adaptable to such use. Other objects and advantages of the invention should become apparent as the description proceeds.

In the drawing:

Figure 1 is a schematic diagram of a system embodying my invention for reproducing sound from phonograph records; and

Figure 2 is a graph illustrating the characteristics of operation of the tone control of my invention.

Referring now to Figure 1, the piezo-electric translator, generally indicated at 10, is physically actuated by the stylus 11 and is connected through circuit 12—16 and conductor 25 to a suitable amplifier 28 which in turn feeds loudspeaker 32 through conductors 30. The circuit referred to consists of conductor 12, a fixed resistance 13, conductor 14, a variable resistance 15 constituting the volume control, and conductor 16. A condenser 19 has one of its terminals connected with an arm 20 of a three point switch 17, the center terminal 22 of which is open. The other two terminals of the switch 21 and 23 are connected, respectively, with conductors 12 and 25 leading from the translator device 10.

With the switch arm 20 in the neutral position shown in the drawing, condenser 19 is ineffectual and the impedance of the pickup circuit is solely that of the fixed resistance 13 and the variable resistance 15 in series in the circuit. This condition results in a volume-frequency relation graphically shown by curve C22 in Figure 2. With switch arm 20 moved to contact terminal 21, the capacitance of 19 is placed in series with the pickup circuit and in parallel with resistance 13 resulting in relative attenuation of the lower frequency signals and emphasizing the higher frequency responses. The result of the series coupling of the condenser 19 is depicted graphically by the volume-frequency curve C21 of Figure 2.

The third terminal 23 of switch 17 being connected with the conductor 23 places condenser 19 in shunt relation with translator 10 when switch arm 20 is moved to contact this terminal and in this condition of the circuit the higher frequency responses are more severely discriminated against resulting in a volume-frequency

relation indicated by curve C23 of Figure 2. It has been found that the above described three circuit conditions provide an adequate control of the sound reproduction under all methods and 5 conditions of detection and that for all ordinary purposes a finer degree of control is unnecessary. It should be observed that the control is accomplished simply by the manipulation of a conventional three point switch which is readily installed and operated and which is not likely to 10 fail in service.

In practice, I have found that a resistance of approximately 1 megohm is suitable for resistance 13 and that $\frac{1}{2}$ megohm resistance is suitable for resistance 15. The capacity of condenser 19 may, of course, be varied depending on the characteristic of the translator but in general it may be in the nature of .0005 microfarad when coupled with a commercial double piezo-electric 20 crystal actuated by a stylus as shown.

It can thus be seen that I have provided a tone control for use as described which accomplishes the objectives initially set out. By the use of a simple arrangement the signal response from 25 the translator is caused to selectively flow either through a circuit having only series resistance in which the various frequencies maintain their normal relative strength, through a circuit having series coupled capacitance in which the lower frequencies 30 are attenuated, or through a circuit having shunted capacitance in which the higher frequencies are attenuated. The arrangement is further simplified by utilizing the same means, specifically the condenser 19, to provide the capacitance in both instances.

In addition to the tone control feature described above, the circuit provides compensation for the recorded loss in the lower frequencies on the record. Referring to Figure 2 of the drawing, the broken line represents the volume or 40 amplitude of the recording and shows the decrease in the lower frequency range. The line C22 represents the response attained when sufficient resistance is placed in the output circuit 45 to render the output proportional to the amplitude of vibration of the pickup stylus. The response is flat at lower frequencies and curves

downwardly in the higher ranges. By coupling the condenser 19 across resistance 13 the higher frequency signals are relatively strengthened, giving a response curve illustrated by line C21 and resulting in high fidelity production.

The above specifically described embodiment of my invention should be considered as illustrative only as obviously many variations in the arrangement of the frequency discrimination method specifically disclosed herein may be made 10 without departing from the spirit or scope of my invention.

What I claim is:

1. In a sound reproducing system, a source of 15 audio frequency signals comprising a piezo-electric translating element, a circuit connecting said element with a sound reproducing assembly, frequency discriminating means comprising two impedance elements connected with said circuit, the first impedance element being a resistance fixed 20 in series relation with said circuit, the second impedance element being a condenser, means to connect said condenser in series relation with said circuit and shunting said resistance, means to connect said condenser in parallel with said resistance and translator, and means to disconnect 25 said condenser from said circuit.

2. A system according to claim 1 in which said last three mentioned means comprise a unitary 30 three position switch.

3. In a sound reproducing system, a source of 35 audio frequency signals, a circuit connecting said source with a sound reproducing assembly, frequency discriminating means comprising two impedance elements connected with said circuit, the first impedance element being a resistance fixed in series relation with said circuit, the second impedance element being a condenser, means to connect said condenser in series relation with said circuit and shunting said resistance, means to 40 connect said condenser in parallel with said resistance and translator, and means to disconnect said condenser from said circuit.

4. A system according to claim 3 in which said last three mentioned means comprise a unitary 45 three position switch.

CREED M. CHORPENING.
